CLAIM

The ornamental design for a combined decanter and stopper, as shown and described.

DESCRIPTION

FIG. 1 is a front elevation of a combined decanter and stopper showing my new design, the rear elevation being identical to FIG. 1;

FIG. 2 is a side elevation thereof, the opposite side elevation being identical to FIG. 2;

FIG. 3 is a top plan view thereof; and,

FIG. 4 is a bottom plan view thereof.

FIG. 1

FIG. 2

FIG. 3

FIG. 4
